ENGINE STARTER GEARING

Daniel P. Kearney, Birmingham, Mich., assignor
to Bendix Aviation Corporation, South Bend,
Ind., a corporation of Delaware

Application March 13, 1942, Serial No. 434,522

4 Claims. (Cl. 74—7)

The present invention relates to engine starter gearing and more particularly to that type of automatically engaging drive in which the gearing is held in mesh until the engine is reliably self-operative.

In the patent to Kearney, No. 2,218,972, a drive is illustrated which utilizes a centrifugal latch cooperating with an abutment on a screw shaft for holding a pinion in engagement with an engine gear. This arrangement has been found to successfully maintain the cranking connection until the connection is intentionally broken by the operator, but under some circumstances it may be preferable to utilize some other abutment than the screw shaft for maintaining the pinion in mesh.

It is an object of the present invention to provide a novel starter drive of the above type which is efficient and reliable in operation and simple and economical in construction.

It is another object to provide such a device which incorporates a latch cooperating with an abutment on a housing for holding the pinion in mesh with the engine gear.

It is another object to provide such a device having an overrunning connection to the pinion permitting the pinion to rotate faster than the starting motor when the engine starts.

Further objects and advantages will be apparent from the following description taken in connection with the accompanying drawing in which:

Fig. 1 is a side elevation partly broken away and in section of a starter drive incorporating a preferred embodiment of the invention.

Fig. 2 is a section taken substantially on the line 2—2 of Fig. 1 showing the latch in normal or idle position; and

Fig. 3 is a view similar to Fig. 2 showing the latch in operative position.

In Fig. 1 of the drawing there is illustrated a housing 1 which may be an extension of the housing of a starting motor not illustrated. A power shaft 2 is journaled in the housing 1 and has fixed thereon in any suitable manner a sleeve 3 having a driving head 4 at one end and a stop nut 5 at the other. A screw shaft 6 is slidably journaled on the sleeve 3 between the drive head and stop nut and has a driven head 7 which is connected for rotation with the driving head 4 by means of a spring 8, the ends of which are attached to anchor plates 9 and 11 non-rotatably mounted on the driving and driven heads respectively.

A pinion 12 is slidably journaled on the power

shaft 2 for movement into and out of engagement with a member such as a gear 13 of an engine to be started, and means for traversing and rotating the pinion from the screw shaft 6 is provided in the form of a nut 14 on the screw shaft and a barrel 15 rigidly connected to the nut and having a swivelled overrunning clutch connection with the pinion. As here shown, this connection comprises an inturned flange 16 on the barrel formed with ratchet clutch teeth adapted to engage corresponding ratchet teeth on a driven clutch member 17 fixed to the pinion 12. Clutch members 16 and 17 are yieldingly pressed into engagement by a light spring 18 retained on the extended hub 19 of the pinion by an abutment ring 20.

According to the present invention means are provided for maintaining the pinion 12 in mesh with the engine gear 13 as long as the power shaft is rotating above a predetermined speed.

As here shown this means comprises an abutment in the housing in the form of a ring 21, and a latch member 22 pivotally mounted on the nut 14 as by means of a pin 23, normally maintained in retracted position as shown in Fig. 2 by means of a spring 24, but arranged to move out into position to engage the abutment 21 as shown in Fig. 3 when rotated above a predetermined speed.

Means for returning the parts to idle position and normally maintaining the pinion de-meshed is provided in the form of an anti-drift spring 25 interposed between the nut 14 on the screw shaft and the stop nut 5 on sleeve 3.

In operation, starting with the parts in the positions illustrated in Fig. 1, rotation of the power shaft 2 is transmitted through sleeve 3 and spring 8 to the screw shaft 6, causing the nut 14 to be traversed along the screw shaft, moving the pinion 12 into engagement with the engine gear 13. When the nut 14 engages the stop nut 5, the longitudinal movement of the pinion and barrel assembly is arrested and the parts are constrained to rotate with the power shaft, thus causing the engine to be cranked. When the engine starts, the pinion 12 is accelerated by the engine gear 13 and overruns its driving connection by disengagement of clutch members 16, 17. The consequent release of the load on the starting motor causes rapid acceleration of the drive including the nut 14. The latch 22 mounted thereon is thus caused to move out into the position illustrated in Fig. 3 where it is positioned to engage the abutment ring 21 in the housing 1 which consequently prevents de-meshing movement of the pinion and barrel assembly. This

situation continues as long as the starting motor remains energized, and if the engine should not continue to be self-operative it will slow down to a speed corresponding to the instant speed of the starting motor which will then resume the cranking operation. When the operator perceives that the engine has been successfully started, he de-energizes the starting motor, and when the power shaft has decelerated below the predetermined minimum speed, the spring 24 operates to withdraw the latch 22, thus permitting the spring 25 to return the parts to their normal positions with the assistance of the frictional torque transmitted through the overrunning clutch members 16, 17.

It will be appreciated that inasmuch as there is relative motion between the latch 22 and the abutment 21 at all times during the operation of the drive, there is no possibility of sticking of the parts and the arrangement of the abutment in the housing permits the incorporation of the invention in existing types of drive with minimum alteration of the parts of the drive.

Although but one embodiment of the invention has been shown and described in detail, it will be understood that other embodiments are possible and that various changes may be made in the design and arrangement of the parts without departing from the spirit of the invention as defined in the claims appended hereto.

What is claimed is:

1. In an engine starter a housing, a power shaft journalled therein, a screw shaft driven from the power shaft, a nut on the screw shaft, a pinion slidably journalled on the power shaft, means including an overrunning connection for traversing and rotating the pinion from the nut, said housing having an abutment, and a centrifugal latch mounted to rotate with the nut engageable with said abutment for preventing traversal of the nut.

2. In an engine starter a housing, a power shaft journalled therein, a pinion slidably journalled on the power shaft for movement into and out of engagement with a member of an engine to be started, actuating means for the pinion including a member having an overrunning clutch connection therewith, said housing having an abutment, and centrifugal means on said member adapted to engage the abutment to prevent longitudinal movement of said member to disengage the pinion.

3. In an engine starter a housing, a power shaft journalled therein, a pinion slidably journalled on the power shaft for movement into and out of engagement with a member of an engine to be started, actuating means for the pinion including a screw shaft connected to rotate with the power shaft, a nut on the screw shaft, a barrel fixed to the nut, an overrunning clutch connection between the barrel and pinion, said housing having an abutment and means on the barrel engageable with the abutment to hold the barrel and pinion in operative position.

4. In an engine starter drive a housing, a power shaft journalled therein, a pinion slidably journalled on the power shaft for movement into and out of engagement with a member of an engine to be started, means whereby rotation of the power shaft traverses the pinion into operative position and then rotates it to drive the engine member, said means including a barrel member having an overrunning clutch connection to the pinion, an abutment in the housing surrounding the barrel, and a centrifugal latch on the barrel adapted to engage the abutment and hold the barrel in operative position as long as it rotates above a predetermined speed.

DANIEL P. KEARNEY.
